METHOD OF MAKING SERPENTINE TUBE FINNED HEAT EXCHANGER AND PRODUCT

Jesse B. Thomas and Edwin H. Wolff, Louisville, Ky., assignors to Reynolds Metals Company, Louisville, Ky., a corporation of Delaware

Application March 5, 1954, Serial No. 414,463

7 Claims. (Cl. 29—157.3)

The present invention relates to a finned heat exchanger, such for example as a finned condenser, and to a method of making it.

Under the Kramer Patent 2,462,511, a multi-layer finned condenser is made as follows: a series of separate lengths of tubing are each simultaneously bent to form separate planar serpentine sections, one for each layer, each section being composed of a series of straight runs connected by return bends; the return bends along one end of each section are flattened to facilitate subsequent assembly; a series of plate fins are stamped and blanked to form a series of rows of slots, one row for each serpentine section, the successive slots in each row accommodating successive pairs of straight runs and the flattened return bend connecting each pair; each section, with its flattened end foremost, is threaded through its row of slots in all fins so that each section forms a separate layer; internal fluid pressure is applied to each layer of tubing to expand the straight runs into firm contact with the fins and to restore the flattened return bends to their original form; and the outlet end of each layer is connected to the inlet end of the next layer by suitably welding, brazing or soldering a return bend fitting thereto.

It is desirable to make this structure of aluminum tubing but this presents a vexatious problem due to the extreme difficulty of producing a good union between the ends of each return fitting and the ends of the layers which it connects.

Aluminum can be soldered or brazed, but this requires the use of a flux, which readily flows into the interior of the tubing where it is difficult to remove. In a refrigerating system the presence of flux within the tubing creates corrosive conditions; hence all traces of it must be removed. Aluminum tubing can be welded by the well-known heliarc process but, in the limited space available, it is difficult to weld completely around each joint of the return bend fitting. Whether the union is made by welding, brazing or soldering, the heat involved anneals the tubing so that in the subsequent step of expanding the tubing by internal pressure, rupture is liable to occur at the annealed areas.

It has been proposed to make a finned condenser coil by stringing fins in spaced banks on a long tube, then bending that tube with the fins thereon to form straight runs joined serially by return bends. The structure thus produced is not rigid because the banks of fins on each straight run are separate, and this method is slow, cumbersome and costly.

Other proposed methods of constructing a heat exchanger from a single length of tubing involve similar disadvantages, and in addition may require bending under conditions where a mandrel cannot be employed, so that it is not possible to make small radius bends. This results in a bulky structure so that the fins must be made larger than necessary, which results in waste of metal. It has been proposed to make a continuous coil multi-layer heat exchanger by bending each vertical return bend on a mandrel in sequence as the horizontal bends are formed

connecting straight runs. However, this method is cumbersome and subject to human error, and is not practical where the coils are to receive fins common to all the straight runs.

5 Finned air cooled condensers are employed in air conditioners where they are subject to the corrosive action of the atmosphere. This is especially pronounced in regions near the ocean where salt spray occurs in the air, and in industrial areas where the air is contaminated by various corrosive fumes. For this reason the condenser should have good resistance to corrosion in addition to good heat exchange properties.

It is an object of the present invention to provide a method for constructing a multi-layer heat exchanger from a single continuous length of tubing, which is readily adapted to mass production methods.

Another object is to bend a continuous length of tubing into a multi-layer heat exchanger by a novel method which involves relatively little handling, and little liability of damaging the tubing during manufacture.

20 Another object is to form a compact multi-layer finned heat exchanger by a novel inexpensive method which eliminates the necessity of making joints between the layers, and which is easy to perform.

25 Another object is the provision of a method for forming a compact multi-layer heat exchanger in which all layers and all return bends, including those which connect one layer to another, are preformed before the fin assembly operation.

30 Another object is to make a rigid finned heat exchanger, comprising a continuous length of tubing bent into sinuous layers integrally joined without separate fittings, by a novel method which enables all layers to be assembled as a unit on a common fin assembly in an easy manner.

35 Another object is the provision of a heat exchanger comprising a continuous length of tubing bent into sinuous layers, which are integrally joined from end to end without separate fittings, and which are mounted on a common fin assembly.

40 Another object is the provision of a condenser or heat exchanger of aluminum tubing which carries a corrosion-resistant coating of good heat conducting properties.

45 The heat exchanger of the present invention is made up of a continuous single length of tubing not only forming a plurality of horizontal layers but also forming the layer connecting return bends, each layer being in heat transfer relation to circumscribing radiator fins which are common to all layers or to any portion thereof. This eliminates entirely the making of joints between layers and provides a compact, rigid structure. Where a slight constriction of the tube passage at the bends is not objectionable, or the radii of the bends are large, the bends may be formed without a mandrel. However, for compactness, bends of small radius are desirable and attempts

50 to make such bends without a mandrel generally result in too great a constriction of the passage at the bend. The method of the present invention is especially applicable for producing multi-layer shapes after all return bends have been made, and therefore the return bends may be made with or without a mandrel as desired.

55 In accordance with the method of the present invention, a single continuous length of tubing, long enough to form a desired number of layers, is sinuously bent to form a serpentine having straight runs extending longitudinally between its front and rear ends and connected by return bends at each end; and, during or after the formation of the serpentine, each of two or more selected runs of the tubing, is separately twisted about its long axis to rotate the succeeding tubing on one side of said run as a unit relatively to the preceding tubing on the other side of said run.

If we assume that a planar serpentine, such as is shown in Figure 1, is made long enough to embrace a two layer condenser, then it may be processed to form two layers by twisting the last straight run of one section, which is to form the first layer, about the long axis of that last run so as to rotate both the next following or layer-connecting return bend and the second section through a first angle, of desired magnitude ranging from 45 to 135°, and then twisting the adjacent or first straight run of the next section about the long axis of that first run so as to rotate the second section in the same direction through a second angle equal to 180° less the value of said first angle. For example, if the first twisting operation rotates both, the adjacent layer-connecting return bend and the remaining tubing, 90° about the axis of the last straight run of the first section, then the first section will extend at right angles to the remaining tubing. Now if we move from the last straight run of the first section to the first straight run of the second section and twist that first run in the same direction 90° about its axis, the second section will rotate into spaced face-to-face relationship with the first section while the interposed layer-connecting return bend extends at right angles to both sections or layers. In other words, by twisting successive last and first straight runs in the same direction through 90° angles, the second section may be made to overlie or underlie the first section and be spaced from it a distance equal to the span or pitch of the layer-connecting return bend. Obviously any desired number of layers may be made by providing a flat serpentine of sufficient length to embrace a desired number of sections and suitably twisting the adjacent last and first runs of successive sections.

It will be understood that the return bends along one end of the original flat serpentine are flattened preferably before the layers are formed so that, after the layers are formed, the flattened end of each layer of the tube assembly may be inserted through the openings of the fin assembly to form what may be termed a loose condenser assembly. Now, by applying internal fluid pressure to the tube assembly, all straight runs of each layer in the tube assembly are simultaneously expanded into firm contact with all fins in the fin assembly so as to produce a rigid structure having good heat transfer contact while all flattened return bends are simultaneously expanded to eliminate their flattened areas and thus restore them to their original shape. Preferably the outer surface of the entire finished rigid assembly is coated to protect it from corrosion, by treatment in a bath comprising chromic acid and fluoride ions with or without an alkali metal complex heavy metal cyanide.

In constructing a finned condenser by the method of the present invention, the layer-connecting return bends may be located all at one end or the other or at both ends. The preferred arrangement locates all inter-layer return bends at one end and all flattened intra-layer return bends at the opposite end. While such location of the inter-layer return bends is not essential, it is preferred because it permits the fins to be made with slot-like openings in rows corresponding to layers without requiring the fins to have any "layer-connecting slots" to accommodate any inter-layer or layer-connecting return bends. Fins of this character, having one or more rows of slots, may be stamped and blanked by the same die.

The invention will be described in greater detail in connection with the accompanying drawing illustrating a preferred method by way of example and wherein:

Figure 1 is a plan view of a serpentine coil formed in one plane;

Figure 2 is a plan view showing a flattened bend;

Figure 3 is an end view of Figure 2;

Figure 4 is a diagrammatic view of a serpentine after a 90° twisting operation, guide lines being used to make the illustration clearer;

Figure 5 is a view of the serpentine coil shown in

Figure 4 after it has been turned to a different position and subjected to a second 90° twisting operation;

Figure 6 is an end view of the coil after a third 90° twisting operation;

Figure 7 is an end view of the completed coil;

Figure 8 is an obverse view of Figure 7 on a larger scale;

Figure 9 is an end elevational view showing the end plate at one end of a bank of fins;

Figure 10 is a plan view of a completed finned condenser, the fins being shown diagrammatically;

Figure 11 is an enlarged section taken on line XI—XI through the left end of one slot on the end plate shown in Figure 9, this section omitting the right half of the same slot and being identical to a corresponding section through a fin; and

Figure 12 is an end elevational view of a multi-layer finned condenser of the type wherein each layer contains two rows of tubes with the straight runs of one row staggered relatively to the straight runs of the other row in the same layer.

Referring to the drawing, Figure 1, the serpentine coil A has an inlet end B, an outlet end C, and a plurality of straight runs joined serially by return or reverse bends. As shown in Figure 1, the straight runs are numbered consecutively from 1 to 36, and the return bends are similarly numbered with a primed number. All the straight runs and return bends lie in a common plane. They are formed from a single length of tubing bent into shape preferably over a mandrel to form short radius reverse bends. The methods of forming such planar coils are known to the art and need not be described here. In Figure 1 only certain coils and bends are indicated by reference numbers, the omitted portion indicated by dash and dot lines being duplications. Thus, the first straight run at the inlet end B is number 1, the first return bend, which connects it to the next adjacent straight run 2, is 1', the second straight run is 2, the next return bend is 2', and so on up to the last straight run 36, which terminates in outlet end C. In other words, there are 18 hair-pin or U-shaped tubes—the first comprising straight runs 1 and 2 connected together by return bend 1' and the last comprising straight runs 35 and 36 connected together by return bend 35'—and these hair-pin or U-shaped tubes are connected in series by the evenly numbered return bends 2' etc.

Where it is desired to string fins upon the finished coil, the return bends at one end of the coil A are flattened. Thus, as illustrated in Figures 2 and 3, a portion of the return bend on apex 1' of the first U-shaped hair-pin tube, is flattened to form a narrow or flat tubular portion 37 joined to the straight runs 1 and 2 by fillets 38, 38' and 39, 39' respectively.

In processing the flat planar serpentine of Figure 1 to form, say a 3 layer condenser, the first step, after the flattening operation, is to bend it to the form shown in Figure 4. In so doing, clamps 41 and 42 are applied to the end portion of the last straight run 24 of the second section or layer, to grip that run firmly. These clamps are then rotated relatively to each other, as by holding clamp 41 fixed and rotating clamp 42, in the counter clockwise direction indicated by the arrow, to the position shown in Figure 4. In other words, run 24 is twisted between the clamps to rotate return bend 24' and the tubes of the third section or layer until they are in a plane which extends substantially at a right angle to the plane of runs 1 to 24 forming the first and second sections or layers.

The coil A is next processed to the form shown in Figure 5. In so doing clamps 41 and 42 are similarly applied to the first run 13 of the second section and one of these clamps is rotated to twist run 13 so as to rotate the first section (runs 12-1 and return bends 12'-1') until the first section extends in a plane at a right angle to the

plane of the second section (runs 13-24 and bends 13'-24'). The form of the coil thus produced is substantially Z shaped and it will be observed that the return bends 12' and 24' are located at that end of the coil from which inlet B and outlet C extend.

In processing the coil of Figure 5 to the form shown in Figure 6, the last straight run 12 in the first section is twisted to make that section overlie the second section as these sections appear in Figure 5. Similarly, in processing the structure shown in Figure 6 to the form shown in Figures 7 and 8, the first straight run 25 in the third section is twisted as heretofore to make the third section underlie the second section as these sections appear in Figure 5. Thus it will be observed that the planar coil of Figure 1 is processed through the forms shown in Figures 5 and 6 to that shown in Figures 7 and 8 by twisting the last run 12 of the first section and the first run 13 of the second section and by twisting the last run 24 of the second section and the first run 25 of the third section. In so doing the return bend 12' is rotated 90° to become the connection for the first and second layers while return bend 24' is rotated 90° to become the inter-layer connection for the second and third sections.

By rotating these return bends (12' and 24') 90°, the layers are spaced a center-to-center distance equal to the pitch of these return bends. Naturally this spacing can be increased or decreased by increasing or decreasing the pitch of these bends. This spacing may also be increased by selecting, for twisting purposes, more widely spaced straight runs such as runs 11 or 10 of the first section and run 13 of the second. The spacing may be decreased by twisting, say run 13, more or less than 90° but it will not normally be practical to twist one tube less than 45° or the other tube more than 135° for layer spacing purposes. In either of these cases, the sum of both twists must equal 180° if the layers are to be in parallel relationship.

For simplicity of illustration the flattened bends of the coil are not shown in Figures 1 and 4 to 7. It will be noted that in showing the coil in its various states of manufacture, the position has been transposed but this is not essential. In the method illustrated for making a three layer coil the middle layer is formed first, but the order in which the layers are formed may be varied as desired.

Figure 9 may be considered as an end elevational view of either an end plate alone or of an assembly of end plates and fins ready to receive the coil of Figure 8, since both views are identical. Viewing Figure 9 as a front end elevational view of an assembly of end plates and fins and Figure 8 as a front end elevational view of a three layer condenser coil, the finished structure shown in Figure 10 is produced by shoving the front or flattened end of the condenser coil of Figure 8 through the rear end of the assembly of Figure 9 until the front end of the Figure 8 condenser coil projects through the front end of the Figure 9 assembly.

This assembly comprises rear and front end plates 45, 46 and a plurality of intermediate fins 47 common to all the runs. Each end plate and fin is provided with a plurality of apertures 48 of the general outline of a dumb-bell, comprising circular portions 49, and a connecting slot 52, which may be formed by stamping or punching a sheet of suitable size. The circular portions 49 are of a size to provide a close fit around the straight runs of the coil, and the narrow slot 52 is of a width to pass the flattened portions 37 of the return bends. Because in the form of coil shown in Figure 8 the flattened return bends 37 in the various layers are in vertical alignment, the apertures 48 in the fins also are arranged in vertical columns.

Referring to Figure 11, which may be viewed as a detail of either an end plate or a fin, it will be seen that the circular end portion 49 of the slot-like aperture 48, is surrounded by a collar or flange 53 suitably formed thereon. It acts as a spacer to hold the fins and end

plates separated. To assemble the fins on the coil, the fins are placed in position on a suitable jig and the coil is inserted, flattened end first, through the apertures 48. The inlet and outlet ends of the coil then are connected to a suitable source of pressure to inflate or restore the flattened bends, the pressure employed preferably being great enough to expand or stretch the diameter of the straight runs into firm contact with the collars 53 and thus provide for good rigidity and heat transfer. The coil then is disconnected from the pressure source. It will be observed that by having the layer connecting return bends all at one end of the coil opposite the flattened end, it becomes unnecessary to provide vertical slots in the fins or end plates. Because of this arrangement, the same die may be used to stamp out one row of slots in one fin or two or more rows in the same fin, as desired.

Where the condenser is constructed of aluminum pipe or tubing with aluminum fins, we impart improved corrosion resistance thereto by immersing it for a short time, for example, one to five minutes at a temperature of about 70 to 90° F., in a bath containing chromic acid, a fluorine compound producing fluorine ions in solution, and with or without the presence of an alkali metal cyanide complex. The following bath illustrates a preferred composition.

10 to 15 g./l. chromic anhydride

3 to 6 g./l. ammonium fluosilicate

2 g./l. up to limit of solubility potassium ferricyanide

30 Upon removing the condenser from the bath it is washed and dried.

In the above example, other fluoride activator ion compounds may be employed as for example, sodium fluoborate, ammonium bifluoride, or complex fluorides and the like, and potassium ferricyanide or the complex cyanides of copper, manganese or chromium may be used in place of potassium ferricyanide. Or if desired, complex cyanides may be omitted from the bath.

This invention is not limited to aluminum tubing but may be employed with tubing composed of copper and other metals. While the manufacture of a three layer condenser, with all three layers in series, is illustrated, this invention may be used to make multi-layer condensers with the layers in series or in parallel or with one or more layers connected in one way to form one set and one or more other layers connected in the same way or different way to form another set with each set intended to be devoted to the same use or to independent uses. Furthermore, the invention contemplates the manufacture of condensers or heat exchangers of the type having one or more layers wherein each layer is formed of a double row of tubes, such as is illustrated in Figure 12. Here the straight runs in one row of one layer are staggered from the straight runs in the second row of the same layer and practically every tube is twisted to rotate the next return bend to the position required by the next straight run.

Having described our invention, we claim:

1. In the method of making a heat exchanger or the like from a serpentine tubing having a series of straight runs extending longitudinally between its front and rear ends and connected serially at said ends by return bends, the steps comprising: gripping a selected straight run of the tubing in a pair of clamps spaced apart along said straight run while leaving the return bends at the opposite ends of said straight run free to move; and turning one clamp about the longitudinal axis of said straight run relative to said other clamp to twist said straight run and swing the tubing portions located on the opposite sides of said straight run relative to each other about said axis while confining said twist to the portion of said straight run located between said clamps.
2. The method of claim 1 wherein: before twisting said selected run, said tubing lies substantially in a common plane; and immediately after said straight run is twisted,

the tubing on opposite sides thereof lie respectively in separate planes which extend at an angle to each other.

3. The method of claim 2 including: selecting a second straight run in one of said tubing portions and repeating said clamp gripping and turning steps on it to twist it and swing a part of said one tubing portion substantially into parallelism with the other tubing portion.

4. The method of claim 3 wherein: said second straight run is connected to said first straight run by a single return bend.

5. The method of claim 4 wherein: said part of said one tubing portion is swung about said second straight run into spaced face-to-face relationship to said other tubing portion to provide a pair of spaced parallel facing sections of tubing connected by a return bend.

6. The method of claim 5 including: flattening the return bends at the front end of said tubing; inserting said tubing with said flattened return bends foremost into a bank of fins having aligned slots shaped to receive said flattened return bends until said bank of fins lies on the straight runs of said tubing; and applying internal pressure to said tubing to distend said flattened return bends to

substantially their original shapes prior to being flattened and to expand the straight runs into firm contact with said fins.

7. The method of claim 6 wherein: the flattening of the return bends is performed prior to the twisting of said tubing.
